D5-27

EX

05379

OR D 14,979

No. 14,979

Apr. 29, 1884

UNITED STATES PATENT OFFICE.

THOMAS HARDCASTLE, OF BRADSHAW WORKS, NEAR BOLTON, COUNTY OF LANCASTER, ENGLAND.

DESIGN FOR THE ORNAMENTATION OF COTTON, SILK, OR OTHER FABRICS.

SPECIFICATION forming part of Design No. 14,979, dated April 29, 1884.

Application filed February 25, 1884. Term of patent 7 years.

To all whom it may concern:

Be it known that I, THOMAS HARDCASTLE, of the firm of James Hardeastle & Co., of Bradshaw Works, near Bolton, in the county of Lancaster, England, bleachers, printers, and dyers, a subject of the Queen of Great Britain, residing at Bolton aforesaid, have invented and produced a new and original Design for the Ornamentation of Cotton, Silk, and other Fabrics, of which the following is a specification, reference being had to the accompanying photograph, forming part thereof, in which—

The parts marked a represent the half-length portrait of the celebrated actor Henry Irving, and the parts marked b represent the half-length portrait of the equally-celebrated actress Ellen Terry.

The "Trial Scene" from Shakespeare's play the "Merchant of Venice" is depicted in that part of the design marked c, and the "Balcony Scene" from the same author's "Romeo and Juliet" in the part marked d.

The remaining part e represents Beatrice and Benedick in another of Shakespeare's plays, "Much Ado About Nothing." The portraits are encircled by wreaths of foliage and appropriate emblems.

I claim—

The design for the ornamentation of cotton, silk, or other fabrics, herein shown and described, the same consisting of the portraits of Henry Irving and Ellen Terry, marked a and b, respectively, and the other parts, marked c, d, and e, and illustrating scenes from three of Shakespeare's plays, as specified.

The foregoing specification of my design for cotton, silk, or other fabrics signed by me this 8th day of February, 1884.

THOMAS HARDCASTLE.

Witnesses:

H. B. BARLOW,

S. WALKEY GILLET,

Both of 4 Mansfield Chambers, St. Ann's Square, Manchester.